United States Patent

Des. 235,767
Patented July 8, 1975

235,767

ALBUM COVER OR THE LIKE

Abraham Bernstein, Forest Hills, N.Y., assignor to Kleer-Vu Industries, Inc., New York, N.Y.

Filed June 29, 1973, Ser. No. 374,885

Term of patent 14 years

Int. Cl. D19—04

U.S. Cl. D19—31

FIG. 1

FIG. 2

FIG. 1 is a front elevational view of an album cover or the like showing my new design; and

FIG. 2 is a cross sectional view taken along line 2—2 of FIG. 1.

The rear surface not shown is plain and unornamented.

I claim:

The ornamental design for an album cover or the like, as shown and described.
